[57] CLAIM

The ornamental design for a combined beverage container and coaster, as shown and described.

DESCRIPTION

FIG. 1 is a front perspective view of a combined beverage container and coaster showing my new design; FIG. 2 is a rear perspective view thereof in an assembled condition;

FIG. 3 is a top plan view thereof in an unassembled condition;

FIG. 4 is a front elevational view of FIG. 3;

FIG. 5 is a bottom plan view of FIG. 3;

FIG. 6 is a left side elevational view of FIG. 4;

FIG. 7 is a right side elevational view of FIG. 4; and

FIG. 8 is a cross-sectional view thereof in an exploded position.

FIG.1
